UNITED STATES PATENT OFFICE

140,554

DESIGN FOR A DISPENSING UNIT

Albert A. Paley, Kew Gardens, N. Y., assignor to
Eagle Automatic Sales Corp., New York, N. Y.,
a corporation of New York

Application November 27, 1944, Serial No. 116,573

Term of patent 14 years

(Cl. D2—3)

To all whom it may concern:

Be it known that I, Albert A. Paley, a citizen of the United States, residing at Kew Gardens, in the county of Queens and State of New York, have invented a new, original, and ornamental Design for a Dispensing Unit, of which the following is a specification, reference being had to the accompanying drawing, forming part thereof.

The figure is a perspective view of a dispensing

unit showing my new design. The left side and back, not shown, are substantially like the right side shown.

The dominant features of the design reside in the portions shown in full lines.

I claim:

The ornamental design for a dispensing unit, as shown and described.

ALBERT A. PALEY.
